US00D723516S

(12) **United States Design Patent**
Kang et al.

(10) **Patent No.:** US D723,516 S
(45) **Date of Patent:** ** Mar. 3, 2015

(54) **SPEAKER**

(71) Applicant: **Samsung Electronics Co., Ltd.**, Suwon-si (KR)

(72) Inventors: **Yun-Je Kang**, Seongnam-si (KR); **Dong-Hee Won**, Seoul (KR)

(73) Assignee: **Samsung Electronics Co., Ltd.**, Suwon-si (KR)

(**) Term: **14 Years**

(21) Appl. No.: **29/476,407**

(22) Filed: **Dec. 13, 2013**

(30) **Foreign Application Priority Data**

Jun. 14, 2013 (KR) 30-2013-0030930
(51) **LOC (10) Cl.** 14-03
(52) **U.S. Cl.**
USPC **D14/214**

(57) **CLAIM**

The ornamental design for a speaker, as shown and described.

DESCRIPTION

FIG. 1 is a front perspective view of a speaker showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the speaker are for environmental purposes only and form no part of the claimed design.
